DESIGN FOR A TRAVELER FOR TWISTING RING

William M. Camp, Glen Ridge, N. J.

Application March 15, 1944, Serial No. 112,911

Term of patent 14 years

(Cl. D17—12)

To all whom it may concern:

Be it known that I, William M. Camp, a citizen of the United States, residing at Glen Ridge, county of Essex, and State of New Jersey, have invented a new, original, and ornamental Design for a Traveler for Twisting Ring, of which the following is a specification, reference being had to the accompanying drawing, forming a part thereof.

Fig. 1 is a side elevational view of a traveler for twisting ring showing my new design; and Fig. 2 is a section on the line 2—2 in Fig. 1.

I claim:

The ornamental design for a traveler for twisting ring, substantially as shown.

WILLIAM M. CAMP.
